UNITED STATES PATENT OFFICE

ROBERT KLINE, OF EAST CLEVELAND, OHIO

VACUUM-CLEANER NOZZLE

Application filed March 30, 1928. Serial No. 265,869.

This invention relates to a vacuum cleaner nozzle.

An object of the invention is to provide a vacuum cleaner nozzle which will roll up threads and similar articles so that they will be caught by the current of air and carried off from the floor or other surface.

Another object is to provide means in a vacuum cleaner nozzle which will centralize 10 the air currents and, therefore, more efficiently carry off the dirt.

Another object is to provide a vacuum cleaner nozzle which may be moved in different angular positions with respect to the operating handle, so as to facilitate working 15 around and under furniture.

Other objects and advantages will become apparent as the description proceeds.

An embodiment of the invention is illustrated in the accompanying drawing, wherein,

Figure 1 is a perspective view of the nozzle disclosing the underside of the same.

Figure 2 is a bottom plan view. 25 Figure 3 is a sectional view taken on line 3—3 of Figure 2, the nozzle being shown as passing over a rug or carpet, and

Figure 4 is an end elevation of the nozzle.

The nozzle comprises an elongated hollow 30 portion 10 forming a main suction chamber provided with an elongated slot on the side which engages the surface to be cleaned, and gradually increasing in depth toward the center thereof, at which point it merges into a connecting pipe 11. This pipe extends from the portion 10 at approximately a 45° angle, and may be either integral with such portion 35 or a separate member attached thereto. An elbow 12 having a reduced end 13, adapted

40 to have a swivel fit within the pipe 11, is used for connecting the nozzle to the operating handle and the other parts of the vacuum cleaner. The angularity of the elbow is such that when the same is moved into certain positions the operating handle will be in a position so that the nozzle may be run around or beneath furniture or other low objects in the room. One of the last mentioned positions of the elbow is clearly shown in Figure 45 3, and it should be apparent that when the

same is revolved 180° that the free end thereof will be projecting substantially vertically.

The main suction chamber or elongated hollow portion 10 of the nozzle is provided with a relatively wide lip 14 across its lower front edge and a relatively narrow lip 15 across its lower rear edge, said lips being connected at the opposite ends of the suction chamber by curved lip portions 15a. The lip 14 is provided with a series of longitudinally extending ribs 16 of less length than the lip forming between the same grooves 17, the height of the ribs 16 being substantially the same as the height of a bead or rib 18 adjacent to the junction point between the lip 15 and the portion 10 of the nozzle. However, the forward part of the lip 14 is inclined at a slight angle upwardly as shown in Figures 3 and 4, so that there will be a small clearance between the front end of such lip and the surface upon which the nozzle is resting. This angle is shown in Figure 4 by the lines A, B, its apex being indicated at 18a. The purpose of this arrangement will be later described. 70

Adjacent each end of the lip 14 but inwardly therefrom are annular or other depressions 19, having apertures 20 extending through the lip and communicating with the exterior of the nozzle. Since the ribs 16 and grooves 17 communicate with the depressions 19, it is quite clear, because of the apertures 20 and a centrally arranged transversely and vertically extending groove 21 communicating with the main suction chamber at the pipe 11, that a limited amount of air will be 80 free to pass through the apertures 20, the grooves 17 and 21 into the suction chamber. 85

The lip 15 adjacent the rear edge of the nozzle has its forward edge rounded, as shown at 22, while its rear edge is provided 90 preferably at the middle portion thereof with a relatively elongated longitudinally extending notch 23. This notch is transversely aligned with the notch 21 in the front lip, and is also arranged beneath the pipe 11, as clearly shown in Figure 2. 95

When the nozzle is pushed across the surface being cleaned, as shown in Figure 3, threads and other articles will pass under the lip because of the inclination of its front

edge and the ribs 16, when the nozzle is forwardly tipped about the point 18a, will act as a comb to roll them into thread-like form so as to be more readily carried away by the air currents. The groove 21 connecting the grooves 17 with the hollow portion 10 permits of a limited suction action which helps to twist and roll such loose matter into string-like form as the nozzle is shoved over the surface being cleaned.

When the nozzle is at the position shown in Figure 3, the lips 14, 15 and 15a surrounding the slot of the main suction chamber or hollow portion 10 form a seal entirely around the same, except for the small air current passing through the apertures 20, grooves 17 and groove 21. Therefore, in order to break this seal and to centralize the suction action of the device it is merely necessary to tip the nozzle backwardly about the rear edge of the lip 15, raising the lip 14 from the surface whereupon the groove or notch 23 serves as a free opening or valve for the ingress of air into the suction chamber or hollow portion 10.

As this notch is arranged at the middle portion of the device and adjacent to the pipe 11, it will be quite apparent that the air current thus brought about will be concentrated and of greater efficiency than were it spread out over the entire extent of the nozzle.

Although a preferred embodiment of the nozzle has been shown and described, it should be understood that the invention is susceptible of various modifications and adaptations within the scope of the following claims; and that the ribs and grooves might be on the rear lip, the notch 23 differently located, or other changes made without departing therefrom.

Having thus described my invention, what I claim is:

1. A vacuum cleaner nozzle having a main suction chamber and a suction slot, a lip arranged on an edge of such slot having ribs and grooves extending longitudinally thereof whereby as the nozzle is passed across a surface loose articles will be curled or rolled up.

2. A vacuum cleaner nozzle having a main suction chamber therein and an elongated slot in the side of the nozzle in communication with the chamber and which engages the surface to be cleaned, said slot being surrounded by lips adapted to make sealing engagement with the said surface, and one of said lips being provided with a series of ribs and grooves extending substantially parallel with said slot.

3. A vacuum cleaner nozzle having a main suction chamber therein and an elongated slot formed therein extending transversely of the direction of movement of the nozzle on the surface to be cleaned, said slot being surrounded by lips which engage the surface to

be cleaned and one of said lips being relatively wide and having a series of ribs and grooves extending substantially parallel with said slot.

4. A vacuum cleaner nozzle having a main suction chamber therein and an elongated suction slot formed in the side of the nozzle communicating with the chamber and which engages the surface to be cleaned, said slot being surrounded by lips making sealing engagement with said surface, one of said lips which extends longitudinally of said slot being relatively wide and having its working face in an inclined plane making a small angle with the working face of the other of said lips, and said first-mentioned working face having ribs and grooves therein extending longitudinally of said slot.

5. A vacuum cleaner nozzle having a main suction chamber and a slot formed therein, a lip arranged adjacent an edge of such slot and adapted to rest upon a surface to be cleaned, said lip having longitudinally extending ribs formed on the underside thereof and a groove formed therein, transversely disposed with respect to said ribs and communicating with said slot and main suction chamber.

6. A vacuum cleaner nozzle having a main suction chamber and a slot formed therein having forwardly and rearwardly extending lips adjacent the opposite longitudinal edges, said forwardly extending lip being provided with longitudinally extending ribs on its underside and said rearwardly extending lip having formed therein adjacent to its rear edge a notch adapted to admit air to said chamber when the nozzle is rocked about said rear edge to raise said forwardly extending lip from the surface being cleaned.

7. A vacuum cleaner nozzle having a main suction chamber and a suction slot having forwardly and rearwardly extending lips adjacent the opposite longitudinal edges of the suction slot of the nozzle, said forwardly extending lip being provided on its under surface with longitudinally extending ribs and grooves communicating with a substantially transversely extending groove, means for admitting air to the outer ends of said grooves, and said rearwardly extending lip having a notch formed therein adjacent its rear edge.

In testimony whereof, I hereunto affix my signature

ROBERT KLINE.
